ROTARY EXPLOSIVE ENGINE

William Weeks, Chicago, Ill.

Application August 25, 1933, Serial No. 686,839

7 Claims. (Cl. 123—16)

My invention relates to rotary explosive engines and more particularly to the type having stationary cylinders, and my object is to provide an engine of this type which includes an arrangement of revoluble impellers and novel means for counteracting harmful tendencies of centrifugal force in the same.

With the above object in view, a better understanding of the invention may be had by reference to the accompanying drawings, in which—

Figure 1 is a plan view of the engine;

Figure 2 is a plan section taken substantially on the line 2—2 of Fig. 4;

Figs 3, 4 and 5, are a group assembly of sections taken respectively on the lines 3—3, 4—4 and 5—5 of Fig. 1;

Fig. 6 is a section on the line 6—6 of Fig. 3;

Fig. 7 is a section on the line 7—7 of Fig. 10;

Fig. 8 is a section on the line 8—8 of Fig. 6;

Fig. 9 is a section on the line 9—9 of Fig. 2, partly broken away;

Fig. 10 is a section on the line 10—10 of Fig. 5; and

Fig. 11 is a section on the line 11—11 of Fig. 3. Referring specifically to the drawings, 15 denotes a typical frame in which the novel engine is mounted, it being understood that the form of this frame may be altered to suit different installation specifications or requirements.

Within the frame 15, the engine extends in the form of three longitudinally aligned units A, B, and C represented by a medial cylinder 16, and terminal cylinders 17 and 18. Arms 15a extend from the sides of the frame to terminate with plates 15b which meet the walls of the cylinders and are bolted thereto as indicated at 15c to support the same.

The respective cylinders are open at the ends and receive terminal single heads 19 and intermediate dual heads 20, the heads being of larger diameter than the cylinders.

It is my intention that the array of cylinder heads rotate as a unit relative to the cylinder assembly together with a set of cylindrical rotors 16a, 17a and 18a located in the respective cylinders. In order to connect the elements of the rotating unit just mentioned, I apply a series of longitudinal tie rods 21 passing through them as clearly indicated in Figs. 2 and 3, the tie rods extending in threaded form beyond the terminal cylinder heads 19 and through hub plates 22 applied externally of such cylinder heads to receive securing nuts 21a which are tightened to make the unit rigid. The hub plates 22 carry trunnions 23 which are journaled in bearings 15d provided in the end portions of the frame. The bearings 15d are shown plain, but it will be understood that they may be provided with rollers or other types of free-running elements

to make the unit run more easily. A flywheel for the engine is not necessary, as the cylinder heads serve in that capacity.

By particular reference to Fig. 3 it will be apparent that the rotor 16a is formed in two halves which receive between them a transverse assembly of impellers 24 and 24a. With the cylinder 16 stationary, it may be assumed that the rotor 16a is centered to operate in the position shown, whereby it is always in contact with the upper wall of the cylinder. Incidentally, I provide a cross strip 25 with suitable packing means to seal the contact of the rotor with the cylinder at this point, and I have not deemed it necessary to specify the particular design of the packing means, as various expedients for this purpose may be employed.

The impellers 24 and 24a are grouped in overlapping relation and are slidable relative to each other and the rotor, means being employed to urge the respective impellers outwardly whereby to maintain contact with the walls of the cylinder as the rotor turns. Thus, the impellers separate as the rotor carries them away from the position shown in Fig. 3, owing to the increasing distance of the cylinder wall from the rotor.

The arrangement of the rotor and impeller assembly indicated in Fig. 3 is intended to serve for the purpose of drawing a gaseous charge into the cylinder 16 and compressing it for discharge from the same into the cylinders 17 and 18. Thus, with the rotor turning in the direction indicated by arrows in Fig. 3, it will be apparent that the impeller 24a will draw a charge from an intake duct 26 located near the top of the cylinder, and that the succeeding impeller 24 will advance behind this charge and compress the same as the rotor continues to turn. For the expulsion of the compressed charge I first provide a valve 27 of the plug type, this valve seating in a housing 28 which is attached by means of bolts 28a to the wall of the cylinder. The valve 27 has a cross duct 27a which is adapted to register with an outlet port 16b made in the cylinder, as shown, that the compressed charge therein may be passed through the duct into a delivery pipe 29 extending from the valve housing 28. It will be understood that the valve 27 is ordinarily closed in order that the compressed charge in the corresponding portion of the cylinder may be built up by the advance of the impeller therein. However, at the proper time, the valve 27 is given a short oscillatory movement in a clockwise direction to bring the duct 27a into registration with the port 16b. While any suitable means for actuating the valve 27 may be employed, I have shown a very simple expedient for this purpose in Fig. 3. One of the dual cylinder heads 20, both of which are circular, is made in diametrically opposite zones with enlargements 20a

leading to prominent enlargements 20b. The valve 27 is made with a crank 27b having a roller 27c riding on the periphery of the particular cylinder head 20. A spring 30 draws the crank 5 27b inwardly to maintain the roller 27c in contact with the said periphery, and it will easily be seen that twice during each revolution of the rotor 16a the enlargement in the cam-like periphery of the cylinder head will procure a short 10 oscillatory movement of the valve 27 with the results mentioned. The frequency of this movement is, of course, due to the fact that two impellers act in turn during each revolution of the rotor. The unit A is intended to act as a compressor 15 and feeder of the gaseous charge to the units B and C, these being identical in construction. Thus, the delivery pipe 29 continues in the form of branches 29a and 29b which connect respectively with intake pipes 31 and 32 of the 20 units B and C. It is essential that this system be so dimensioned that its capacity is equal to the volume of the compressed charge in the unit A, just before the valve 27 is opened to pass such charge into the delivery pipe 29. Thus, the 25 contents of the delivery system will be transferred by way of the valve 33 of the unit B or C into the combustion space thereof, this space having the same volume just before ignition as the compressed charge in the unit A just before release 30 into the delivery system. By being spread through the delivery system and the combustion space the compressed charge loses half of its pressure. However, the valve 33 closing before firing, half of the distributed charge remains in 35 the delivery system and helps build up pressure as the next compressed charge is fed, so that after a few revolutions of the engine the charges in the combustion chamber have the same pressure as those in the compression unit. Thus, no loss of 40 compression occurs, and during the operation of the engine the pressure is constant between the final portion of the compression chamber in the unit A, the delivery system, and the initial portion of the combustion chamber in the unit B or C when the valve 27 and the corresponding valve 45 33 are open. With full compression in the combustion chamber, it follows that the explosion will have full force.

The intake pipes 31 and 32 for the units B and C lead into valve housings 33a containing valves 33, which are constructed and operate precisely as the one for the unit A, except that they are only actuated once during each revolution of the unit B or C as indicated by the single 50 cam enlargement 20b in Fig. 4 or 19c in Fig. 5 developed from such of the cylinder heads 20 and 19 as are most convenient. The units B and C being intended for the combustion of the charges entering the same are essentially of the 55 same design as the unit A, except that the rotors 17a and 18a therein are only split on one side to accommodate single impellers 24b and 24c. Taking the unit C as an example, and the direction of rotation to be as per arrows in Fig. 5, 60 it will be seen that the impeller 24c is just ahead of the charge being fed into the cylinder space behind the same. A spark plug 34 is carried by the cylinder head in this space, and when the latter has filled to a predetermined volume, the 65 valve closes and a suitable ignition arrangement causes the spark plug to fire and explode the charge. The impeller now draws the rotor around, the explosive gases expanding in a relatively large chamber of the cylinder whereby to 70 exert a driving impulse upon the impeller 75

through the most part of a revolution and issue from the cylinder through the exhaust duct 35 so spent that no appreciable back pressure or noise will occur.

It will be noted that the cam enlargement 19c 5 in the unit C is set with an 180° rotary spacing from the corresponding enlargement 20b of the unit B, indicating that the valves 33 in the respective units operate in turn at every half revolution of the rotor assembly. This sequence is in 10 harmony with the feed from the unit A, so that the charge therefrom is fed to the units B and C in corresponding succession, whereby to procure a power impulse at each half revolution of the rotor assembly. 15

Fig. 6 clearly shows the assembly of impellers 24 and 24a in plan, and it will be seen that these impellers are in lateral contact with the inner sides of the dual cylinder heads 20, seating in grooves 20c made in the same. These are made 20 the entire width of the cylinder heads, as indicated in Figs. 3 and 8, in order to accommodate the dual impellers 24 and 24a throughout the 25 length of their respective strokes. In the combustion units B and C, however, the corresponding 30 grooves 20c need not be cut across the entire 35 faces of the cylinder heads, as only a single impeller—24b or 24c—operates in each unit, and the grooves need only be long enough to allow 40 for the strokes of the single impellers therein. The impellers are, however, maintained in end- 45 wise contact with the walls of the cylinder 16 by 50 extending each impeller radially with a pair of lugs 24d from which pins 24e are directed inwardly to seat in annular grooves 16e made in enlargements 16f at the ends of the cylinder 16. These 55 grooves are cut with their outer walls very slightly clearing the outer sides of the pins 24e, and the latter positioned to ride along the inner 60 walls of the grooves. While this relation maintains 65 the impellers in contact with the cylinder wall, it also allows sufficient clearance in the outer portions of the grooves 24e to permit the impellers to make a closer contact with such wall. This 70 contact is procured by pressure against 75 ledges 24f and 24g of the impellers as will be explained later. The cylinder ends are also formed by smaller annular grooves 16g to carry packings 16h effective against the cylinder heads and the lugs 24d to seal the cylinders from leakage. 80

Fig. 3 shows that the impellers 24 and 24a are identical in construction, having their outer edges inclined to a greater radius on the advancing side of the impellers. It is seen that the impeller 24a makes a proper seat with the wall 55 of the cylinder, but owing to the departure of such wall from the rotor as the latter turns, the angle of the impeller end changes toward the wall of the cylinder to a degree represented by the impeller 24. However, this change does not impair 60 the contact of the impeller with the cylinder wall, as a part of the impeller end is always in contact therewith. In fact, I have provided an expedient whereby the pressure in the cylinders will assist the impellers to maintain engagement with 65 the cylinder walls. This expedient is represented by an angular cross enlargement 24f on the advancing sides of the impellers 24 and 24a at the point of contact with the cylinder wall. As the 70 gaseous charge becomes compressed by the advance of one of these impellers, the pressure is not only against the advancing face of the enlargement 24f but also against the inner face thereof, this pressure overcoming what friction 75 may exist between the impeller and the walls of 80

the rotor channel or of the cylinder head-guide-slots 20c in which the impeller slides, thus easing the sliding motion of the impellers. In the units B and C, the enlargement is indicated at 5 24g and is on the rear side of the respective impellers, since that is where the pressure of the explosion occurs. In all cases, the periphery of the corresponding rotor is recessed as indicated at 10 24h to accommodate the enlargement when the particular impeller reaches the inward limit of its stroke. Thus, it is seen that the forces of combustion and compression are utilized to hold the impellers in firm contact with the walls of the stationary cylinders, relieving the impeller pins 15 24e of this function as soon as the engine begins to rotate. The centrifugal force in the impellers does not add to the forces referred to, as I have provided neutralizing means therefor, as later described.

20 It is natural that the impellers will have a tendency to slide outwardly from the effects of centrifugal force when the rotors are in operation, and I have therefore provided means to counteract such tendency. Thus, in the case of the units 25 B and C, a single installation owing to the use of a single impeller, is more easily apparent and will first be explained.

Referring particularly to Figures 5 and 10 it will be seen that the impeller 24c is provided 30 with weights 24n at its inner end, these weights being designed to counterbalance the heavier working end of the impeller. Thus, when the impeller is entirely within the rotor—at the beginning of its stroke—it is perfectly balanced on 35 each side of the center of rotation and consequently will not be drawn outwardly by centrifugal force. However, as the impeller moves outwardly in the course of its stroke, the balance will be destroyed, the centrifugal force acting upon the outward end of the impeller being greater than the centrifugal force acting upon the weighted end. Consequently, the excessive 40 friction between the impeller and the cylinder wall resulting from this condition—which increases in proportion to the weight of the impeller, the length of its stroke, and the speed of 45 rotation—is detrimental to the satisfactory functioning of a rotary engine of this type. I have therefore invented a structure which provides for 50 perfect equalization or counter-balancing of this deleterious force.

Referring further to Figs. 5, 10 and 11, the centrifugal counterbalancing structure, which operates in conjunction with impeller 24c, consists of three principal sections: (1) a weight 39, with reduced end portions 39a adapted to slide in radial slots 20d cut in contiguous cylinder heads 19 and 20; (2) an angular lever 36 provided with a short arm 36c and a longer slotted 55 arm 36a, said angular lever being journaled on a cross rod 37 whose ends are fitted into contiguous cylinder heads 19 and 20; and (3) a connecting link 38 which is pivoted at one end to weight 39 at 39c, and pivoted at the other end at 36d to short arm 36c of lever 36. To accommodate this structure an opening has been provided in the impeller at 24i, and the end of the impeller is medially split at 24j as shown in Figs. 10 and 5, forming an opening which is spanned 60 by a cross pin 24k. The angular lever 36 with the connecting link 38 extends through the opening in the impeller at 24i, and the slotted arm 36a is linked onto the pin 24k, as shown in Figs. 5 and 10. Thus, as the impeller reciprocates in the course of its stroke, the pin 24k will slide along 65

the longitudinal slot 36b in arm 36a, causing the angular lever 36 to turn on its pivot 37 such that the connecting link 38 will cause weight 39 to slide in its guides 20d. Therefore, it can be seen that the centrifugal force exerted on weight 39 5 counteracts the centrifugal force exerted on the impeller 24c. It should be recalled that as the impeller lies entirely within the rotor at the beginning of its stroke, it is balanced by the weights 24n, as previously explained, and is consequently 10 not affected by centrifugal force. In this position the centrifugal force exerted on weight 39 will pull directly against the cross rod or pivot 37; and, consequently, the counterbalancing mechanism will not be effective upon the impeller. However, as the impeller moves outwardly in the course of its stroke, the pin 24k slides along slot 36b in arm 36a, causing the angular lever 36 to swing on its pivot at 37. 15 This causes the short arm 36c to form an angle 20 with the connecting link 38, thus drawing weight 39 toward the center of rotation. It will be seen that the angle formed between the short arm 36c and the connecting link 38 increases the leverage in favor of the pull exerted by weight 25 39 as the impeller moves outwardly in its stroke; therefore, despite the fact that the weight 39 is drawn toward the center, thus decreasing the radius of its rotation and consequently reducing the centrifugal force acting upon it while at the 30 same time the centrifugal force acting upon the impeller is increasing by virtue of the increasing radius of rotation as the impeller moves outwardly, the increase in leverage is sufficient to 35 compensate for this. Thus, the outward force exerted by the impeller is always exactly equal to the outward force exerted by the weight 39, regardless of the speed of the engine; consequently, the centrifugal force acting upon the impeller is perfectly counterbalanced at each 40 and every point of its stroke.

The expedient just described applies similarly to the two impellers in the unit A as is shown in Fig. 3, except that in this case, the connecting links 38 prevent the cross rods 37 from proceeding directly across the cylinder space, requiring such rods to be made with offset cranks 37a, as shown in Fig. 11, in order to clear the links 38. It is also apparent in Figs. 3 to 5 that the rotor 16a is somewhat larger than the rotors 16b and 16c in order to provide sufficient internal space 45 for the double centrifugal-force counteracting mechanism. As the increase in rotor size would reduce the volume of the chamber between the rotor and the cylinder wall, I have increased the 50 length of the cylinder and the corresponding rotor, as apparent in Figs. 1 and 2, to render the working chamber volume of the unit A the same as for the units B and C.

The weights 24n on the impellers 24b and 24c 55 are intended to counterbalance the impellers at their inner ends, as the impellers have large openings and are therefore much lighter in those zones. Weights 24m have also been provided at the inner ends of the impellers 24 and 24a, as 60 shown in Fig. 3, for the same reason. The weights also serve to equalize the centrifugal stresses of each impeller when it is at the inward limit of its stroke.

For average purposes, it is desirable that an 65 engine of this type be air cooled in order to save weight, material and accessory cooling system. I have therefore provided a novel air cooling arrangement which is self-contained and requires no accessory parts, although it is understood that 70 75

where the engine is to be made for power plant or heavy duty purposes a suitable water cooling arrangement may be provided. In general it is noted that the cylinders are made with a series of peripheral cooling fins 40. In addition, I have extended the terminal cylinder heads 19 with a radial series of cooling fins 41, these being provided with a closure ring 42 whereby to form a series of radial passages between the ring and the head as indicated in Figs. 2 and 9. A similar series of passages is formed by casting the dual cylinder heads 20 with a series of radial webs 43, as clearly shown in Figs. 2 and 6. The assembly of the terminal cylinder heads 19 with the hub plates 22 is made with a circular series of arcuate slots 44; and opposite these, the dual cylinder heads are formed with a similar series of slots 44a, the exposed series of slots being interconnected by a plurality of bores 45 made in the stock of the rotors 17a and 18a, as clearly indicated in Figs. 2, 4 and 5. Thus, what heat accumulates in such rotors as adjoining the combustion chambers of the engine, is drawn outwardly from the bores 45 through the radial passages 43a of the cylinder head 20 by centrifugal force when the engine is in operation, thus causing cool air to enter from outside the engine through slots 44. I also have cooling means for the space internally of the rotors, starting with a circular series of arcuate slots 46 made in the assembly of the terminal heads 19 with the hub plates 22. These slots permit atmospheric air to enter the internal space of the rotors; and a circular series of passage ducts 47 is made in the dual cylinder heads 20 as clearly shown in Fig. 2 to permit the passage of the air from the rotors of the units B and C to that of the unit A. Here the rotor 16a is made with a central series of slots 48 connecting with a plurality of cross bores 49 clearly shown in Figs. 2, 3, and 8, these cross bores connecting endwise with a series of arcuate slots 50 made in the contiguous walls of the dual cylinder heads 20. These slots, of course, connect with the internal space of each dual cylinder head and permit air from the center of the engine to be drawn out by centrifugal force by way of the radial passages of the said cylinder heads. It is thus seen that the novel engine is not only cooled along the exterior of its cylinders as is the conventional practice, but has self-contained means for dissipating heat from within it as it operates.

From the above description, it will be apparent that I have provided an engine which is compactly built, has no delicate parts or springs involved in its vital operations, has self-contained means to overcome detrimental effects of centrifugal motion, and takes advantage of such motion to draw atmospheric air and discharge heated air in order to keep the engine cool. Further, the engine has no complicated mechanisms to regulate it or time it, employing a valve and cam mechanism of utmost simplicity and in keeping with standard engineering. Further, the fact that the rotor and cylinder heads are rigidly assembled as a unit gives the engine durability and enables simple and uniform means to be employed for the prevention of leakage. Finally, it will be evident that efficiency in operation is obtainable by the divisional design of the engine into a compressing and charging unit coupled with a pair of working units in a relation to operate these in alternation for balanced running. I have shown the external cooling arrangement of the

engine exposed, but it is feasible to enclose the engine with a jacket to protect it from dust or dirt and also confine the air drawn from the atmosphere more closely to the fins and passages therebetween, bottom openings being provided for the escape of the heated air and oil or other impurities that may be drawn from the rotating cylinder heads. 5

I claim:—

1. In a rotary engine, the combination with a cylinder and a rotor eccentrically positioned therein; of an impeller operable radially of the rotor and with its outer end in contact with the cylinder wall, and means for counteracting the excessive centrifugal pressure of the impeller against the cylinder wall at different radial positions of the impeller in proportion to said pressure at such positions. 10
2. In a rotary engine, the combination with a cylinder, a rotor eccentrically positioned therein, and heads for the cylinder and jointly operable with the rotor, of an impeller operable radially of the rotor and in contact with the cylinder wall, and means for counteracting the excessive centrifugal pressure of the impeller against the cylinder wall at different radial positions of the impeller in proportion to said pressure at such positions, said means comprising a pivot between the cylinder heads, an angle lever operative with the angle on the pivot, a sliding connection between the inner portion of the impeller and one arm of the angle lever, and a weight connected to the other arm of the latter. 20
3. In a rotary engine, the combination with a cylinder, a rotor eccentrically positioned therein, and heads for the cylinder and jointly operable with the rotor, of an impeller operable radially of the rotor and in contact with the cylinder wall, and means for counteracting the excessive centrifugal pressure of the impeller against the cylinder wall at different radial positions of the impeller in proportion to said pressure at such positions, said means comprising a pivot between the cylinder heads, an angle lever operative with the angle on the pivot and having one of its arms 30 formed with a longitudinal slot, a cross pin in the inner portion of the impeller and passing through said slot, a weight at a point laterally of the impeller, and a link pivotally connected at its ends to the other arm of the angle lever and to the weight respectively. 40
4. The structure of claim 2, the inner portion of the impeller having an opening, and the angle lever extending from the pivot into said opening. 45
5. The structure of claim 3, the cylinder heads having aligned radial recesses, and the weight extending with its ends into the latter for guidance. 55
6. The structure of claim 1, said means comprising an auxiliary weight laterally of the impeller, and a mechanism between the impeller and the weight to draw the latter in an inward radial direction as the impeller moves outwardly. 60
7. The structure of claim 1, said means comprising an auxiliary weight laterally of the impeller, and an angle lever making connection with its arms to the impeller and the weight to draw the latter in an inward radial direction as the impeller moves outwardly, the lever being designed to lend the weight a leverage advantage over the impeller in response to centrifugal influence in the weight. 65

WILLIAM WEEKS,
